CLAIM

The ornamental design for a camera and motion sensor housing, as shown and described.

DESCRIPTION

FIG. 1 is a perspective view showing our new design mounted on a tree in phantom outline;

FIG. 2 is a front elevational view;

FIG. 3 is a left side elevational view;

FIG. 4 is a rear elevational view;

FIG. 5 is a right side elevational view;

FIG. 6 is a top plan view;

FIG. 7 is a bottom plan view; and,

FIG. 8 is a front elevational view with the camera access door partially opened and the camera shown in phantom outline.

The tree and camera shown in phantom lines are to illustrate an environment only and form no part of the claimed design.
